UNITED STATES PATENT OFFICE.

WILLIAM M. WATTIE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

DRIVE FOR LOOM PATTERN MECHANISM.

Application filed April 7, 1926. Serial No. 100,403.

This invention relates to a driving connection between one of the constantly moving shafts of a loom and a pattern mechanism of the type set forth in patent to 5 Knowles No. 134,992, and it is the general object of the invention to improve upon the means heretofore employed for holding one of the bevel gears on the upright shaft of such a loom in proper position.

10 The so-called Knowles head employs a pair of spaced oppositely moving mutilated gear cylinders between which lie a plurality of thin vibrator gears mounted on vibrator levers which are controlled as to vertical 15 position by a pattern chain so as to move the gears into operative relationship with respect to one or the other of the cylinders. The latter are driven by bevel gears secured to an upright shaft the lower end of which 20 is supported in a step bearing and has keyed thereto a guide collar through which extends a driving pin secured to a vertically moving clutch. The pin is received by a bevel gear which heretofore has been held 25 in raised position by means of a collar held against downward movement on the upright shaft by upsetting a portion of the latter immediately above the step bearing. With 30 this construction it has been found inconvenient to remove the bevel gear on the shaft when the same becomes broken or worn and it is a more particular object of my invention to thread a portion of the shaft and mount thereon a threaded collar a portion 35 of which is split to provide a clamp by means of which the collar can be held in adjusted position on the threaded portion of the shaft. The bevel gear is provided with a recess in the lower face thereof which receives the split collar, the latter acting as 40 a support for said gear to hold the same in proper relation with respect to the collar keyed to the shaft.

45 With these and other objects in view which will appear as the description proceeds, my invention resides in the combination and arrangement of parts hereinafter described and set forth in the claim.

50 In the accompanying drawings wherein I have shown a convenient embodiment of my invention,

Fig. 1 is a front elevation of the end portion of a loom showing the upright shaft

for the Knowles head equipped with my invention,

55 Fig. 2 is an enlarged vertical section through the lower end of the upright shaft and step bearing therefor, being in effect an enlargement of the part shown in cross section in Fig. 1,

60 Fig. 3 is a detail horizontal section on line 3—3 of Fig. 2, and

Fig. 4 is an enlarged vertical section on line 4—4 of Fig. 3.

65 Referring more particularly to the drawings it will be seen that I have provided a loom side 10 having arches 11, one of which is shown in the drawings, and a head frame 12. Mounted for rotation in opposite directions in said head frame are upper and lower mutilated cylinder gears 13 and 14, respectively, having shafts 15 and 16, respectively. Keyed to said shafts are bevel driving gears 17 which mesh with and are driven by corresponding bevel gears 18 secured to the 70 upper end of the upright shaft 19. The latter shaft extends through a bearing 20 secured to the head frame and rotates constantly during the running of the loom.

75 A heel pin 21 mounted on the head frame 80 supports the outer end of a plurality of vibrator levers one of which is indicated at 22, each lever having mounted thereon a vibrator gear 23 which is located between the upper and lower cylinders. Pivotally attached as at 24 to each gear 23 is a connector 25 the inner end of which has operative engagement as at 26 with a harness lever 27 moving about a center 28 fixed in the arches of the loom. A pattern mechanism indicated at 29 controls the vertical position of the vibrator levers 22 to determine which of the mutilated cylinders will 85 actuate the vibrator gears 23.

90 In order to drive the upright shaft 19 I 95 may connect the same with the bottom shaft 30 passing through a bearing 31 secured to the loom frame and having keyed to the outer end thereof a bevel gear 32. The latter gear meshes with a corresponding bevel gear 33 mounted loosely on the bottom of the shaft 19 and adapted to receive the lower end of a driving pin 34 which is riveted in a clutch 35 and passes through a collar 36 keyed to the shaft 19. By means of lever 100 105 37 the clutch 35 and driving pin may be

lifted so as to permit free rotation of gear 33 independently of upright shaft 19. The bearing 31 is provided with a step 38 shown more particularly in Fig. 2 which receives 5 the reduced lower end 39 of the upright shaft. The matter thus far described is of common construction and forms no part of my present invention.

In carrying out my improvements I provide the lower end of the shaft 19 with threads 40 located immediately above the reduced end 39, said threads extending upwardly from a shoulder 41 on an intermediate section 42 of the shaft located between 15 that part of shaft 19 on which the clutch 35 slides and the reduced end 39. The threaded portion extends somewhat above the bottom of the recess 43 formed in the lower part of bevel gear 33 and has threaded thereon 20 a collar 44 shown more particularly in Figs. 2, 3, and 4. Said collar is threaded internally as shown at 45 in Fig. 3 and is split or slotted as at 46, the slotted part extending slightly beyond the center line of the 25 collar as indicated in Fig. 3. Extending across the slot, preferably centrally of the slotted portion, is a screw 47 passing freely through the lower part and threaded into the upper part of the slotted portion of the collar 44. The collar is made of material at least slightly resilient so that as the screw is tightened in place the two parts separated by the slots 46 are drawn together on the threads 40 to serve as a clamp to prevent 30 creeping or angular motion of the collar relative to the upright shaft 19. The split collar may have holes 48 extending therethrough for cooperation with a spanner wrench not shown.

Under normal operation the bottom shaft 30 rotates constantly and when the parts are in the position indicated in the drawings will transmit rotary motion to shaft 19 through bevel gear 33, pin 34, and collar 45, thereby driving the head motion located adjacent the upper end of the shaft 19. When it is desired to remove any portion of the construction located at the bottom of the shaft 19 such as the clutch 35 keyed to 50 the collar 36 or gear 33, the bearing 31 is let down to permit access to the collar 44, after which the screw 46 is slackened until the split portions of the collar 34 assume their normal non-clamping position. The 55 split collar may then be removed by means of

a spanner wrench as previously described. The defective parts may then be removed and replaced by others, after which the collar may be replaced and the screw 47 tightened, care being taken to establish proper spacing between the collar 36 and the gear 33 so as to permit free movement of the same when the head is disconnected by lever 37 but to prevent undue play between the gears 32 and 33.

From the foregoing it will be seen that I have provided a very simple device for supporting the bevel gear located at the bottom of the upright shaft of the well-known Knowles loom and that the collar hereinbefore described can be removed and replaced repeatedly without disfigurement of any portion of the upright shaft 19 and that by means of the vertical adjustment of the collar 44 I am enabled to establish a better adjustment between the gear 33 and the keyed collar 36 than has been possible heretofore.

Having thus described my invention, it will be apparent that changes and modifications may be made therein by those skilled in the art without departing from the spirit and scope of the invention, and I do not wish to be limited to the details herein disclosed, but what I claim is:

In driving means for pattern mechanism for looms including a pair of oppositely constantly rotating spaced actuating cylinders to cooperate with vibrator gears mounted on vibrator levers controlled by pattern mechanism, said loom also including a driving shaft having a bevel pinion secured thereto and bevel pinions for said actuating cylinders, in combination, an upright shaft interposed between the driving shaft of the loom and said cylinders having bevel pinions secured thereto to mesh with the bevel pinions of said cylinders, a bevel pinion on the lower end of the upright shaft to mesh with the pinion on the driving shaft, threads cut on a reduced part of the upright shaft at the lower end thereof, an internally threaded supporting collar on said lower portion of the upright shaft to support the bevel pinion on the lower end of said shaft, and means to support said upright shaft.

In testimony whereof I have hereunto affixed my signature.

WILLIAM M. WATTIE.
